UNITED STATES PATENT OFFICE.

EDWARD R. McELLIGOTT, OF BROOKLINE, MASSACHUSETTS, ASSIGNOR TO HEYWOOD-WAKEFIELD COMPANY, OF BOSTON, MASSACHUSETTS, A CORPORATION OF MASSACHUSETTS.

DESIGN FOR A REED CHAIR.

Application filed January 3, 1928. Serial No. 24,740. Term of patent 3½ years.

To all whom it may concern:

Be it known that I, EDWARD R. McELLIGOTT, a citizen of the United States, residing at Brookline, in the county of Norfolk and Commonwealth of Massachusetts, have invented a new, original, and ornamental Design for a Reed Chair, of which the following is a specification, reference being had to the accompanying drawing, forming part thereof, in which the figure is a perspective view of the chair, showing my new design.

I claim:

The ornamental design for a reed chair, as shown.

Dated this twenty-second day of December, 1927.

EDWARD R. McELLIGOTT.
